ONSVILLE E. PRAY, OF PORTSMOUTH, NEW HAMPSHIRE.

Letters Patent No. 73,647, dated January 21, 1868.

IMPROVEMENT IN MACHINES FOR CUTTING DYE-WOOD.

The Schedule referred to in these Letters Patent and making part of the same.

TO ALL WHOM IT MAY CONCERN:

Be it known that I, ONSVILLE E. PRAY, of Portsmouth, in the county of Rockingham, and State of New Hampshire, have invented a new and improved Machine for Cutting Dye-Woods; and I do hereby declare that the following is a full, clear, and exact description thereof, which will enable others skilled in the art to make and use the same, reference being had to the accompanying drawings, and to the letters of reference marked thereon.

This invention relates to a new and improved machine for cutting dye-woods into pieces or chips directly from the log. The invention consists of a rotary drum, provided with cutters at its periphery, and arranged in relation with an inclined trough, containing a feed-bar, which is operated by a rack and pinion, as herein-after fully shown and described. In the accompanying sheet of drawings—

Figure 1 is a side sectional view of my invention, taken in the line $x x$, fig. 2.

Figure 2, a plan or top view of the same.

Figure 3, a section of the same, taken in the line $y y$, fig. 1.

Similar letters of reference indicate like parts.

A represents a frame, which may be constructed in any proper manner, to support the working parts, and B represents a drum, the shaft α of which has its bearings in standards $b b$, at the sides of the frame. This drum has its arms c cast or formed with chambers d , at their outer ends, to receive cutters C , the cutting-edges of which project through slots $d x$, in the periphery of the drum, the slots extending entirely across the periphery, and admitting of the free escape of the chips from the log. The cutters C are formed with serrated edges, and they may be all in one piece, or composed of a plurality of pieces, and secured in the chambers d , by set-screws f or keys, as will be fully understood by referring to fig. 3. D is an inclined trough, on the frame A, the lower or depressed end of which is quite close to the periphery of the drum B. This trough is of sufficient width and depth to receive the log of dye-wood to be cut, and within said trough there is placed a bar, E, having a rack, g , at its under side, into which a pinion, h , gears, said pinion being on a shaft, F, on the framing, and having a crank or hand-wheel, G, on one end, as shown in fig. 2.

The operation is as follows: The drum B is rotated by any convenient power, and the log of dye-wood to be chipped or cut is placed in the trough D, in front of the feed-bar E, the latter, by turning the shaft F, being forced down through the medium of the rack and pinion, and keeping the end of the log in contact with the periphery of the drum B, the cutters C chipping the end of the log.

The device is extremely simple and efficient, will perform its work rapidly, and may be constructed at a very moderate cost.

Having thus described my invention, I claim as new, and desire to secure by Letters Patent—

The drum B, constructed as described, its radial arms c provided with chambers d in their outer ends for the reception of the adjustable cutters C, and the periphery of said wheel, provided with transverse slots $d x$, as herein described for the purpose specified.

ONSVILLE E. PRAY.
